(57) **CLAIM**

We claim the ornamental design for flexible agitator fins, substantially as shown and described.

DESCRIPTION

FIG. 1 is a perspective view of a flexible agitator fin, shown in condition of use with an agitator that is shown in broken lines and forms no part of the claimed design.

FIG. 2 is an enlarged elevation view thereof shown separately for clarity of illustration.

FIG. 3 is a greatly enlarged right side elevation view thereof.

FIG. 4 is a greatly enlarged left side elevation view thereof.

FIG. 5 is a greatly enlarged top plan view thereof; and,

FIG. 6 is a greatly enlarged bottom plan view thereof.
